UNITED STATES PATENT OFFICE.

ELERT A. HILL, OF LOS ANGELES, CALIFORNIA.

LOCK.

1,368,556.

Specification of Letters Patent. Patented Feb. 15, 1921.

Application filed February 14, 1920. Serial No. 358,742.

To all whom it may concern:

Be it known that I, ELERT A. HILL, a citizen of the United States, residing at Los Angeles, in the county of Los Angeles and State of California, have invented new and useful Improvements in Locks, of which the following is a specification.

This invention relates to a lock and particularly pertains to a lock of the permutation type.

It is the general object of this invention to provide a combination or keyless lock which is especially applicable for use on hinged closures such as the doors of buildings, safes, lock-boxes, vehicles, and the like, but which may be adapted for use in any manner in which keyless locks may be employed.

The principal specific object of this invention is to provide a lock of the above character embodying the following features; to wit—

First: A selective mechanism for controlling the retraction of a locking element adapted to be readily placed out of operation to permit the lock being opened either with or without the selective mechanism.

Second: A construction whereby the selective mechanism may be readily set to operate at numerous combinations.

Third: An arrangement whereby the lock may be readily fitted to be operated as a latch from one side thereof and freely opened from that side when the selective mechanism is either in or out of operation.

Fourth: An assemblage of elements so disposed as to preclude "picking" of the lock and to render extremely difficult and remote the possibility of discovering the unknown locking combination.

Fifth: A form and arrangement of parts which will permit economical construction and the ready assemblage of the lock and so designed as not to be liable to get out of order but in which repairs and replacements may be easily made.

Other objects will appear hereinafter.

The preferred embodiment of my invention is illustrated in the accompanying drawings, in which—

Figure 1 is a view of the lock as seen in vertical section;

Fig. 2 is a detail horizontal section as seen on the line 2—2 of Fig. 1.

Fig. 3 is a detail in perspective illustrating the bolt operating mechanism.

Fig. 4 is a detail horizontal section as seen on the line 4—4 of Fig. 1.

Fig. 5 is a detail in plan as seen on the line 5—5 of Fig. 1.

Fig. 6 is a detail in perspective as seen in the direction of the arrow 6 in Fig. 5, illustrating the adjustable catch.

Fig. 7 is a perspective view of the catch as removed.

Fig. 8 is a view in perspective showing the exterior of the lock.

Fig. 9 is a detail in section and elevation showing the locking controlling mechanism.

Fig. 10 is a view in vertical section illustrating a modified form of the invention.

Fig. 11 is a detail horizontal section as seen on the line 11—11 of Fig. 10.

Fig. 12 is a detail in perspective as seen in the direction indicated by the arrow 12 in Fig. 11.

Fig. 13 is a detail in perspective illustrating a modified form of the bolt operating mechanism.

Fig. 14 is a detail in perspective showing a means whereby the selective mechanism of the lock may be thrown out of operation so that the lock may be operated independent thereof.

More specifically, 15 indicates the locking casing, which may be of any suitable construction but which is here shown as comprising a face plate 16, a back plate 17, and an intermediate partition plate 18, which may be assembled and connected together in any desired manner. Mounted to reciprocate in the space between the plates 16 and 18 is a bolt 19, which is normally disposed in an advanced position by means of a spring 20 bearing between a shoulder 95 on the bolt and a guide flange 21 preferably formed on the partition plate and extending through the face plate is a rotary shaft 22, which also projects through the partition plate and extends adjacent to the inner end of the bolt 19, and which shaft is normally idle and adapted to be rotated without effecting operation of the bolt but which is designed to be operatively connected to the bolt to retract the latter by means of a bill 23 pivoted on the bolt and having a hook 24 on its outer end adapted to be moved into position to be engaged by a projection 25 on the shaft whereby rotation of the shaft will operate, when the hook is 110 engaged by the projection, to retract the bolt in opposition to the spring 20; the pro-

jection 25 being designed to ride out of engagement with the hook on continued rotation of the shaft after complete retraction of the bolt, so as to release the latter and permit it to be restored to its normal locking position. The means for moving the bill in and out of its shaft engaging position is here shown as comprising a cam 26 carried by an oscillatory disk 27 and which cam consists of an upwardly projecting body on the disk 27 having a longitudinally extending, inclined slot 28 through which a bar 29 on the bill extends; the walls of the slot 28 acting on the bar 29 on oscillation of the disk 27 to raise and lower the bill. The disk 27 is loosely pivoted on the portion of the shaft 22 extending through the partition plate 18, thus positioning the oscillatory plate in the space between the partition plate and the back plate. To effect connection between the cam and the bill the partition plate is formed with a slot 30 through which the cam extends.

A spring 31 is here shown as wound around the shaft 22 beneath the partition plate and connected at its ends to the partition plate and the disk in such manner as to operate to advance the latter in one direction and which direction is such as to cause the cam 26 to elevate the bill; the end of the slot 28 serving on engagement with the bar 29 to limit the advance movement of the disk under the action of its spring.

Means are provided whereby retraction of the disk may be effected by retraction of the bolt and comprises a projection 32 extending upwardly from the disk through the slot 30 and disposed in the path of travel of a downward projection 33 on the inner end 40 of the bolt in such manner that as the bolt is moved inwardly it will engage the projection 32 when the disk is in its advanced position and act to retract the disk in opposition to the spring 31. Means are provided 45 for temporarily holding the disk in its retracted position, which embodies a catch 34 mounted on some one or more of a series of spring arms 35 arranged beneath the disk and bearing thereagainst; the catch being 50 adapted to engage a shoulder 34' formed on the disk when the latter is in its retracted position. The spring arm 35 carrying the catch is designed to be depressed to disengage the catch from the disk to permit the latter to be advanced under the action of the spring and thereby throw the bill into 55 position to be engaged and retracted by rotation of the shaft, and the means for depressing the spring arm comprises a selective mechanism by which a certain device or 60 series of devices must be chosen from a number of corresponding devices and operated to depress the particular spring arm carrying the disk catch.

65 The selective mechanism is here shown as

comprising a bank of push buttons 36 arranged at suitable intervals around the shaft 22 and projecting through the face plate and partition plate with their inner ends disposed adjacent to the upper face of 70 the disk opposite openings 37 formed in the latter and which openings are arranged over the spring arms 35; the spring arms and push buttons corresponding in number and which number may be varied as occasion 75 may require. The push buttons 36 are normally held in their outermost position clear of the disk by suitable springs, which are shown in Fig. 1 as comprising helical 80 springs 38 bearing between the partition plate and a shoulder on the push button, and illustrated in Fig. 10 as comprising plate springs 39 engaging slots in the push buttons.

It will now be seen that by depressing the 85 push button opposite the spring arm carrying the disk engaging catch, the inner end of the push button will pass through the opening 37 and depress the spring arm to disengage the catch. It will be noted, however, 90 that if the opening 37 be circular, movement of the disk will be prevented even though the catch is disengaged therefrom by reason of the stem of the push button projecting into the opening into engagement with 95 the walls thereof, and that on retraction of the push button the catch will be reengaged so that even though the proper push button be selected from the bank, its depression 100 would not effect operation of the lock.

As it may be desired in some instances that the lock be set to operate by the depression of a single push button, some one or more of the openings 37 may be elongated to form slots, as indicated at 40 in Fig. 4, 105 which will permit the necessary movement of the disk.

As a means for increasing the number of combinations necessary for operating the lock, a second bank of push buttons 41 is 110 provided, which is arranged in radial alignment with the push buttons 36 and the stems of which project through the partition plate opposite openings 42 formed in the disk. The push buttons 41 are provided for the 115 purpose of engaging the outer ends of the spring arms 35 when the latter are in their depressed position, as shown in Fig. 9, so as to hold the catch out of engagement with the disk on retraction of the push button 36 120 initially operated to release the catch; the slot 42 through which the particular push button extends for engaging the selected spring arm being elongated so that when the stem of the push button is passed there- 125 through to hold the spring arm depressed, the disk will be advanced by its spring on retraction of the previously depressed button 36. As a means for enabling engagement of the outer end of the spring arm by 130

the outer push button, the spring arm is formed with an upturned end 43, which terminates adjacent to the inner edge of the slot 42 and is adapted to be moved into the particular path of travel of the stem of the push button on depression of the spring arm, so that the end of the spring arm will engage the end of the push button stem when the latter is depressed, as shown in 10 Fig. 9.

A double row of push buttons is thus provided and two push buttons are arranged opposite each spring arm 35. By providing two or more of the catches 34, depression of 15 more than two push buttons will be necessary in order to effect operation of the lock and by varying the locking position of the catches, that is by arranging the catches on various combinations of the arms, a large 20 number of lock controlling combinations may be obtained.

As a means for enabling changing of the particular combination of a lock, a catch 34 is mounted on each spring arm and adapted 25 to be disposed thereon either in position to engage a shoulder 34' on the disk or out of operative relation thereto, for which purpose the catch is formed like a spring clip, as shown in Fig. 7, and embodies inturned 30 portions 44 adapted to engage the sides of the spring member and to extend into a notched portion 45 adjacent to the outer end of the spring member so as to be engageable with the disk or to be disposed in a 35 notched portion 46 adjacent to the inner end of the spring arm in an inoperative position.

As a further means of varying the possible combinations of the lock, means are provided for converting either of the elongated 40 openings 42 in the disk into a short opening so that when the stem of a push button 41 is inserted in the opening, the disk will be held against movement. This means is here 45 shown as comprising a pair of arms 47 and 48 pivoted on the shaft 22 to extend over the face of the disk, as particularly shown in Fig. 2, and which arms are designed to be held against movement relative to the disk 50 in any desired adjusted position by engaging the outer ends of the arms in notches 49 formed in the edge of the disk. In like manner the arms may be adapted to extend over the elongated slots 40. The possible 55 combinations may be further varied by changing the arrangement of the slots and openings on the disk as occasion may require.

If desired, the lock may be adapted to be 60 opened from the inner side thereof independent of the combination controlling mechanism in which event the constructions shown in Figs. 10 and 13 may be employed.

Fig. 10 shows a connecting rod 50 attached 65 to the bolt 19 and connected to a wrist pin 51

on a shaft 52 extending through the back cover plate 17 and fitted with a knob 53 by which the shaft may be rotated to retract the bolt. In the construction shown in Fig. 13, the bill 23 is formed with a downturned end 70 54 adapted to project in front of a pin 55 carried on a sleeve 56 encircling the shaft 22 and revoluble independent of the latter; the sleeve 56 being adapted to extend through the rear cover plate and to be rotated to effect retraction of the bolt. 75

As means for rendering the lock operable independent of the push buttons, the projection 32 may be constructed in the form of a pin 32', as shown in Figs. 10 and 14, which 80 pin is reciprocably mounted in the disk and extends through a slot 57 in the back plate and is acted on by a spring 58 to be normally disposed with its upper end projecting in the path of travel of the bolt. By withdrawing 85 the pin 32' out of the path of travel of the bolt, this bolt may be freely retracted without retracting the disk, and the disk being disposed in its forward position will act through the cam to hold the bill in its upper- 90 most position, so that on rotation of the shaft, the bolt may be retracted; the bar 29 on the bill being of such length as to permit reciprocable movement of the bolt. A sliding wedge shaped clip 59 may be mounted on 95 the back plate 17 to engage a head 60 on the stem 32' to hold the latter in its withdrawn position.

The push buttons 36 and 41 are all spring 100 pressed and normally disposed in their outer positions, and where plate springs are employed, as shown in Figs. 10 and 11, the springs 39' engaging the outer row of buttons 41 may be formed on the plate from which the springs 39 are struck. By this 105 construction, the use of separate helical springs for each push button is obviated and a construction provided whereby all of the springs required for acting on the push buttons may be struck from a single plate. 110

In the operation of the invention, when the parts are disposed in their normal position, the bolt will be in its advanced position, the disk will be retracted, the bill will be in its lowermost position, and the shaft 115 will be free to rotate inoperatively, as shown in Figs. 1 and 10. To open the lock, the proper button or combinations of buttons is depressed to effect release of the disk, as before described, whereupon the spring acting thereon will advance the disk to cause the cam to raise the bill in such position that rotation of the shaft will cause the projection thereon to engage the hook so that continued rotation of the shaft will retract the bolt. 120 The bolt in moving rearwardly will engage the projection 32 on the disk so that when the bolt reaches its fully retracted position, the disk will be likewise fully retracted and reengaged by the catch or catches on the 130

spring arms, at which point the bill will be disengaged from the projection on the shaft so that the bolt will be returned to its advanced position by the spring acting thereon.

5 When it is desired to operate the lock independent of the push buttons, the latter are first operated to cause the disk to move to its advanced position, whereupon the pin 32' will be positioned in the forward end of the slot 10 57 and on being withdrawn and engaged by the clip 59 will be disposed out of the path of travel of the bolt, so that on retraction of the bolt the disk will not be retracted therewith. The bill will then be normally disposed 15 in its uppermost position and in readiness to be engaged by the projection on the shaft.

In the application of the invention here shown the lock casing comprises a door adapted to be hinged in a suitable casing, 20 and as a means for locking the door on its opposite edges, a pair of the bolts 19 is provided together with their operative connections to the disk, both of which bolts are adapted to be operated in a corresponding 25 manner.

While I have shown and described a specific embodiment of the invention, I do not limit myself to the exact details of construction shown but may employ any construction 30 or arrangement of the parts and equivalents thereof as may come within the scope of the appended claims.

I claim:

1. In a lock, a normally advanced bolt or 35 latch, a shaft normally free to rotate inoperatively, a double bank of selective push buttons, one of which is normally inoperative, means controlled by one of the buttons in the other bank for rendering a button 40 operative in the other bank, and means controlled by the last named button for operatively connecting the shaft and bolt whereby turning of the shaft will retract the bolt.

45 2. In a lock, a normally advanced bolt or latch, a shaft normally free to rotate inoperatively, a double bank of selective push buttons, one of which is normally inoperative, means controlled by one of the buttons in 50 the other bank for rendering a button operative in the other bank, and means controlled by the last named button for operatively connecting the shaft and bolt whereby turning of the shaft will retract the bolt, said 55 means adapted on the retraction of the bolt to automatically disconnect the bolt and shaft to restore the bolt to its locking position.

60 3. In a lock, a normally advanced bolt, a rotary shaft, a projection on said shaft, a bill pivoted on said bolt adapted to be moved in and out of a position to be engaged by the projection on the shaft and normally 65 out of such position when the bolt is advanced, means for raising and lowering said

bill, a series of selective push buttons controlling said last named means, means whereby depression of certain of said push buttons will cause said bill operating means to elevate the bill whereby rotation of the 70 shaft will retract the bolt, and means whereby retraction of the bolt will reverse said bill operating means.

4. In a lock, a normally advanced bolt, a 75 rotary shaft, a projection on said shaft, a bill pivoted on said bolt adapted to be moved in and out of a position to be engaged by the projection on the shaft and normally 80 out of such position when the bolt is advanced, a cam for raising and lowering said bill, an oscillatory plate carrying said cam, spring means for advancing said plate in one direction to cause the cam to elevate the bill, a series of selective push buttons for controlling said plate, and means whereby 85 depression of certain of said buttons will cause the plate to be advanced by said spring means whereby the cam will operate to elevate the bill so that rotation of the shaft will retract the bolt. 90

5. In a lock, a normally advanced bolt, a rotary shaft, a projection on said shaft, a bill pivoted on said bolt adapted to be moved in and out of a position to be engaged by the projection on the shaft and normally 95 out of such position when the bolt is advanced, a cam for raising and lowering said bill, an oscillatory plate carrying said cam, spring means for advancing said plate in one direction to cause the cam to elevate the 100 bill, a series of selective push buttons for controlling said plate, means whereby depression of certain of said buttons will cause the plate to be advanced by said spring means whereby the cam will operate to elevate the bill so that rotation of the shaft will retract the bolt, and means whereby 105 rotation of the bolt will restore said plate to its initial position.

6. In a lock, a normally advanced bolt, a 110 rotary shaft, a projection on said shaft, a bill pivoted on said bolt adapted to be moved in and out of a position to be engaged by the projection on the shaft and normally 115 out of such position when the bolt is advanced, a cam for raising and lowering said bill, an oscillatory plate carrying said cam, spring means for advancing said plate in one direction to cause the cam to elevate the 120 bill, a series of selective push buttons for controlling said plate, means whereby depression of certain of said buttons will cause the plate to be advanced by said 125 spring means whereby the cam will operate to elevate the bill so that rotation of the shaft will retract the bolt, and a projection on said disk positioned to be engaged by said bolt on retraction thereof whereby retraction of the bolt will act to restore the disk to its initial position. 130

7. In a lock, a normally advanced bolt, means for retracting said bolt normally out of connection therewith, an oscillatory disk, a spring for moving said disk in one direction, means whereby retraction of the bolt will move the disk in the other direction, a catch for holding the disk under spring tension independent of the bolt, selective means for disengaging said catch to permit 10 the disk to advance, and means operated by advance movement of the disk for positioning the bolt and its retractive means in operative relation to each other.

8. In a lock, a normally advanced bolt, 15 means for retracting said bolt normally out of connection therewith, an oscillatory disk, a spring for moving said disk in one direction, means whereby retraction of the bolt will move the disk in the other direction, 20 a catch for holding the disk under spring tension independent of the bolt, selective means for disengaging said catch to permit the disk to advance, means operated by advance movement of the disk for positioning 25 the bolt and its retractive means in operative relation to each other, and means whereby the disk may be thrown out of operative relation to the bolt.

9. In a lock, a normally advanced bolt, 30 means for retracting said bolt normally out of connection therewith, an oscillatory disk; a spring for moving said disk in one direction, means whereby retraction of the bolt will move the disk in the other direction, a 35 catch for holding the disk under spring tension independent of the bolt, selective means for disengaging said catch to permit the disk to advance, means operated by advance movement of the disk for positioning 40 the bolt and its retractive means in operative relation to each other, and means whereby the bolt may be retracted independent of the first named retractive means.

10. In a lock, a movable disk having an 45 opening therein, an arm extending beneath said opening, means on said arm normally operating to hold the disk against movement, means operating through said opening to depress the arm and release the disk, 50 means for advancing the disk, a bolt, normally inoperative means for advancing said bolt, and means whereby advance movement of the disk will render the bolt advancing means operative.

55 11. In a lock, a movable disk having an opening therein, an arm extending beneath said opening, means on said arm normally operating to hold the disk against movement, means operating through said opening to depress the arm and release the disk, 60 said means embodying a normally retracted push button stem so arranged that on depression thereof the arm will be depressed, means for advancing the disk, a bolt, normally inoperative means for advancing said

bolt, and means whereby advance movement of the disk will render the bolt advancing means operative.

12. In a lock, a movable disk having an opening therein, an arm extending beneath 70 said opening, means on said arm normally operating to hold the disk against movement, means operating through said opening to depress the arm and release the disk, said means embodying a normally retracted push button stem so arranged that on depression thereof the arm will be depressed and a second push button stem so arranged 75 relative to said arm that on being depressed it will engage the arm only when the latter is in a depressed position, means for advancing the disk, a bolt, normally inoperative means for advancing said bolt, and means whereby advance movement of the disk will render the bolt advancing means 80 operative.

13. In a lock, a pair of reciprocal spring pressed and normally retracted push button stems, and a spring arm extending beneath one of said stems and terminating to 90 one side of the path of travel of the other stem and adapted on being depressed to project beneath said last named stem in position to be engaged by the latter.

14. In a lock, a spring arm fixed at its 95 inner end, a push button stem arranged over said arm and adapted on depression to depress said arm, and a second push button stem having a path of travel normally passing said arm, said arm being adapted on depression thereof to be advanced into the path of travel of said second stem.

15. In a lock, a spring arm fixed at its inner end, a push button stem arranged over said arm and adapted on depression to 105 depress said arm, a second push button stem having a path of travel normally passing said arm, said arm being adapted on depression thereof to be advanced into the disk on depression of the arm, and lock 110 mechanism controlled by said arm.

16. In a lock, a spring arm fixed at its inner end, a push button stem arranged over said arm and adapted on depression to depress said arm, a second push button 115 stem having a path of travel normally passing said arm, said arm being adapted on depression thereof to be advanced into the path of travel of said second stem, a movable disk, a spring for advancing said disk in one direction, a catch on said arm engageable with said disk to hold the latter in a retracted position and adapted to release the disk on depression of the arm, and lock 120 mechanism controlled by said disk.

17. In a lock, a spring arm fixed at its inner end, a push button stem arranged over said arm and adapted on depression to 125 depress said arm, a second push button stem having a path of travel normally pass-

ing said arm, said arm being adapted on depression thereof to be advanced into the path of travel of said second stem, a movable disk, a spring for advancing said disk 5 in one direction, a catch on said arm engageable with said disk to hold the latter in a retracted position and adapted to re-

lease the disk on depression of the arm, lock mechanism controlled by said disk, and means whereby depression of the first 10 named stem will lock the disk against movement.

ELERT A. HILL.
